US00D668959S

(12) **United States Design Patent**
Brown et al.

(10) **Patent No.:** **US D668,959 S**
(45) **Date of Patent:** **** Oct. 16, 2012**

(54) **BOTTLE**

(75) Inventors: **Samantha Brown**, Crystal Lake, IL (US); **Neil Enciso**, Palatine, IL (US); **Brent Lindberg**, DeKalb, IL (US)

D217,129 S 4/1970 Beeby
D220,030 S 3/1971 Plummer
D220,866 S 6/1971 Weckman
D222,610 S 11/1971 Plummer
D225,155 S 11/1972 Bismark

(73) Assignee: **Tropicana Products, Inc.**, Bradenton, FL (US)

FOREIGN PATENT DOCUMENTS

CA ID120024 3/2008

(Continued)

(**) Term: **14 Years**

(21) Appl. No.: **29/378,649**

Primary Examiner — Carol P Rademaker

(22) Filed: **Nov. 8, 2010**

(74) Attorney, Agent, or Firm — Banner & Witcoff, Ltd.

(51) LOC (9) Cl. **09-01**

(57) **CLAIM**
The ornamental design for a bottle, as shown and described.

(52) U.S. Cl. **D9/541; D9/542; D9/563; D9/569; D9/574**

DESCRIPTION

(58) **Field of Classification Search** D9/516, D9/530, 537-544, 546, 550-552, 556, 560, D9/563-564, 569, 571, 574-575; 215/381-385
See application file for complete search history.

FIG. 1 is a top, front, right perspective view of a bottle showing a first embodiment of our new design; FIG. 2 is a front view thereof;
